UNITED STATES PATENT OFFICE.

HENRY A. OLSSON, OF BROOKLYN, NEW YORK, ASSIGNOR OF ONE-THIRD TO ALBERT WILLIAMSON AND ONE-THIRD TO EDWARD WILLIAMSON, OF NEW YORK, N. Y.

STAPLING-MACHINE.

No. 873,888.

Specification of Letters Patent.

Patented Dec. 17, 1907.

Application filed January 29, 1907. Serial No. 354,703.

To all whom it may concern:

Be it known that I, HENRY A. OLSSON, a citizen of the United States, residing in Brooklyn, in the county of Kings and State 5 of New York, have invented certain new and useful Improvements in Stapling-Machines, of which the following is a specification.

This invention has reference to machines that automatically sever a length of wire, 10 bend it into the form of a staple, and thereupon force such staple through a number of sheets or leaves, or an article readily pierced, and thereupon clinch the projecting ends of the staple.

15 The object of the invention is to provide in a mechanism of this character, means for causing approach of the anvil to the wire guide in order to facilitate the feeding of the end of the wire from the guide into the opening or slot in the anvil, and thereupon causing recession of the anvil in order to permit it to coöperate with the bending member or former to bend the staple from the blank.

In the accompanying drawings illustrating 25 one embodiment of my invention, Figure 1 is a front elevation of a portion of the machine, the table and coöperating means that serve to clinch the staple being omitted. Fig. 2 is a plan view. Fig. 3 is a fragmentary 30 perspective view of the machine. Figs. 4, 5 and 6 are each a vertical section on the line 4—4 indicated in Fig. 9. Fig. 7 is a side elevation. Fig. 8 is a rear elevation. Fig. 9 is a horizontal section on the line 9—9 indicated in Fig. 1. Fig. 10 is a bottom plan 35 view of certain parts. Fig. 11 is a vertical section on the line 11—11 indicated in Fig. 9. Fig. 12 is a perspective view of the former member detached.

40 In the construction herein set forth, the anvil is slidably mounted on a carrier that is normally retained with the anvil adjacent the wire guide, but which carrier is engaged by a part of the former and shifted away 45 from the wire guide into position for engagement with the former when brought down. The anvil is mounted to reciprocate in the said carrier, whereby when engaged by the driver it will retreat and leave the 50 staple in the former to be engaged by the driver and forced into the article. In the construction herein set forth, on a frame member M is mounted a wire guide 12, shown in the form of a tube having a reduced end 55 with its bore slightly larger than the size of

the wire to be used. The wire is fed into and through the tube by passing between rollers 13 and 14 suitably operated and timed to feed a length of wire at intermittent periods. A former 15 is mounted to slide between 60 suitable guide blocks 16 and 17, and is shown as reciprocated by having a pin or roller 18 slidable in a cam slot 10 in a disk 19, that is secured on a driving shaft 20. An anvil member is mounted on a carrier 22 and 65 comprises a head 23 having a transverse slot 24, and a shank portion 25 slidable in a bore 26 in the carrier 22. The carrier 22 has a stem 27 passing through a bore in the guide member 17 and has a head 28 on the 70 outer end of the stem. A plate spring 29 secured on the head 28 engages the rear end of the shank 25 of the anvil, and presses the anvil outward to its normal position. The carrier is thereby movable in a path whereby 75 the anvil can be shifted toward and from the wire guide 12, to bring its slot 24 in close proximity with the bore from which the wire emerges.

The carrier is normally supported with the 80 anvil adjacent the wire guide, and retained at such position by means of a plate spring 30 fast to the guide member 16 and bearing against the head 28 of the carrier. The former 15 is provided with leg portions 31 85 and 32 spaced a sufficient distance to straddle the anvil head 23 when the anvil is shifted to registering position therewith. To shift the anvil to such position, the carrier 22 is provided with an inclined face 33 90 that is engaged by an abutment portion 34 on the rear of the former 15, as best shown in Figs. 8 and 12. This will shift the carrier and anvil, against the force of the spring 30, to bring the anvil into alignment with the 95 former. A cutter 35 is secured to the former and severs the wire close to the end of the guide tube 12, before engagement by the former legs with the projecting portions of the wire on each side of the anvil slot. The 100 further descent of the former will cause the leg portions to bend down the wire projecting on each side of the anvil. The legs of the former may be provided with small channels or slots 9 on their opposing faces for engagement with the legs of the staple to retain the latter in position.

A driver 40 is shown slidable in the former 15 and is operated by a link 41 pivoted on the disk 19 by crank pin 42. These me n 105

bers are timed relatively with the operation of the former that after the former has descended and bent the staple, the driver 40 is brought down to engage the staple. The upper face of the anvil is shown as inclined, and is engaged by the end of the driver, whereby the anvil is caused to retreat against the pressure of the spring 29, leaving the staple supported in the grooves in the former. Thereupon, the advance of the driver forces the staple into the article. As soon as the former is moved upwardly by its operating cam slot, the disengagement of the block 34 with the inclined surface of the carrier for the anvil, will permit the anvil to be returned to its normal position in proximity with the wire guide, by the action of the spring 30.

The feed rolls 13 and 14 are operated from the cam disk 19, to feed the wire for the distance of one length, before the former engages with the anvil to shift it from its position adjacent the wire guide over to position for engagement with the former. In the construction illustrated, a lever 43 is suitably pivoted on the frame M and has a roller 44 engaging the periphery of the cam 19 by which the lever is rocked. A pawl 45 carried by the lever engages a ratchet wheel 46 by which roller 14 is rotated. By this arrangement, it will be seen that the anvil 23 being positioned in close proximity to the guide tube 12 when the wire is fed from the tube to the slot in the anvil, which will insure the end of the wire properly entering the anvil slot, and prevent any possibility of the wire striking the side of the anvil and bending to stop the operation of the machine. The slot in the anvil is of sufficient size to permit the wire readily passing through it, and the wire is fed a sufficient distance, so that when the anvil is shifted to position of alinement with the former, and the wire severed, the wire will project with the two leg portions an equal distance on each side of the anvil. Evidently, the loose fit of the wire in the anvil will permit the movement of the anvil to position of coöperation with the former, by sliding along the length of wire, not yet severed.

A guide member comprising a head 47 containing the slot 48, has its shank 49 secured in the carrier 22, with the slot 48 in alinement with the slot 24 in the anvil whereby the wire fed through the anvil will pass through this guide slot and be prevented from moving outward in the slot in the anvil. The slot 48 in this guide opens downward to permit the bending of this leg of the staple upon the operation of the former.

Having thus described my invention, I claim:

1. In a stapling machine, a former guided to reciprocate, a slotted anvil organized to coöperate with the former, a wire guide, the

anvil being supported for movement from a position to be engaged by the former to a position adjacent the wire guide to receive the wire in its slotted portion, means for moving the anvil to a position adjacent the guide, the machine being organized to move the anvil to the position for engagement with the former.

2. In a stapling machine, a former guided to reciprocate, a slotted anvil organized to coöperate with the former, and a wire guide, the anvil being supported for movement from a position to be engaged by the former to a position adjacent the wire guide to receive the wire in its slotted portion, the anvil being also movable in a path transverse to said movement.

3. In a stapling machine, a former guided to reciprocate, a slotted anvil organized to coöperate with the former, a wire guide, the anvil being supported for movement from a position to be engaged by the former to a position adjacent the wire guide to receive the wire in its slotted portion, means for moving the anvil to the position adjacent the guide, and means for causing the advance of the former to engage the anvil to shift the anvil to position for engagement with the former.

4. In a stapling machine, a former guided to reciprocate, a slotted anvil organized to coöperate with the former, a wire guide, the anvil being supported for movement from a position to be engaged by the former to a position adjacent the wire guide to receive the wire in its slotted portion, a spring to yieldably retain the anvil adjacent the guide, the machine being organized to move the anvil to position for engagement with the former.

5. In a stapling machine, a former guided to reciprocate, a slotted anvil organized to coöperate with the former, a wire guide, the anvil being supported for movement from a position to be engaged by the former to a position adjacent the wire guide to receive the wire in its slotted portion, a spring to yieldably retain the anvil adjacent the guide, and means for causing the advance of the former to engage the anvil to shift the anvil to position for engagement with the former.

6. In a stapling machine, a former guided to reciprocate, a slotted anvil organized to coöperate with the former, a movable carrier on which the anvil is movably supported, a wire guide, and means for moving the carrier to bring the anvil adjacent the guide to receive the wire in its slotted portion, the machine being organized to move the carrier to bring the anvil to position for engagement with the former.

7. In a stapling machine, a former guided to reciprocate, a slotted anvil organized to coöperate with the former, a movable carrier on which the anvil is movably supported, a wire guide, means for moving the carrier to bring the anvil adjacent the guide to re-

ceive the wire in its slotted portion, the machine being organized to move the carrier to bring the anvil to position for engagement with the former, and a driver, the anvil being movable on the carrier by engagement with the driver to recede from its former-engaging position and permit engagement of the driver with the staple.

8. In a stapling machine, a former guided to reciprocate, a slotted anvil organized to coöperate with the former, a movable carrier on which the anvil is movably supported, a wire guide, a spring arranged to yieldably retain the carrier with the anvil adjacent the guide to receive the wire in its slotted portion, the carrier being in position for direct engagement with the former to be thereby shifted against the tension of said spring to bring the anvil to position for engagement with the former, and a driver arranged to engage the anvil and shift it on the carrier to permit engagement of the driver with the staple in the former.

9. In a stapling machine, a former guided to reciprocate, a slotted anvil organized to coöperate with the former, a movable carrier on which the anvil is movably supported, a wire guide, means for feeding wire intermittently through the guide, and means for moving the carrier to bring the anvil adjacent the guide to receive the wire in its slotted portion, the carrier being in position for direct engagement with the former to be shifted upon advance thereof to bring the anvil to position for engagement with the former and after the wire end has been fed into the anvil.

10. In a stapling machine, a former guided to reciprocate, a slotted anvil organized to coöperate with the former, a movable carrier on which the anvil is movably supported, a wire guide, means for feeding wire intermittently through the guide, a spring arranged to yieldably retain the carrier with the anvil adjacent the guide to receive the wire in its slotted portion, the carrier being in position for direct engagement with the former to be thereby shifted against the tension of said spring to bring the anvil to position for engagement with the former and after the wire end has been fed into the anvil, and a

driver arranged to engage the anvil and shift it on the carrier to permit engagement of the driver with the staple in the former.

11. In a stapling machine, the combination of an operating member, a former guided to reciprocate, means to reciprocate the former from the operating member, a wire guide, feeding means operated to feed wire intermittently to the guide, a movable carrier, an anvil movably mounted on the carrier for coöperation with the former, the carrier being movable to shift the anvil toward and from the guide to receive the wire, a spring arranged to normally retain the carrier with the anvil in proximity to the guide, the carrier having an inclined abutment face, an abutment face on the former in position to engage the carrier abutment face upon advance of the former to shift the carrier and bring the anvil in position to receive the former, a driver movable adjacent the former, means for reciprocating the driver, the anvil having an inclined face arranged to be engaged by the driver when in said coöperating position, and thereby caused to shift permitting engagement of the staple in the former with the driver, and a spring on the carrier arranged to retain the anvil normally in coöperating position relative to the driver.

12. In a stapling machine, the combination of a former guided to reciprocate, a movable carrier, a slotted anvil mounted on the carrier, and organized for coöperation with the former, a guide to feed wire to the anvil, means for shifting the carrier to move the anvil toward and from the guide, and a slotted directing member mounted on the carrier with its slot alining with the slot in the anvil but opening in a different direction to permit bending of the staple leg by the former, the said member being located removed from the anvil on the carrier to permit operation therebetween of the former portion for bending that leg of the staple.

Signed at Nos. 9 to 15 Murray street, in the city, county and State of New York, this 24th day of January, 1907.

HENRY A. OLSSON.
